UNITED STATES PATENT OFFICE.

THOMAS C. FORBES, OF HOPKINS, MINNESOTA, ASSIGNOR TO WATERS-ENTER COMPANY, OF MINNEAPOLIS, MINNESOTA.

ELECTRIC SWITCH.

Application filed May 19, 1926. Serial No. 110,121.

My invention relates to electric switches, and an object is to provide a switch having fixed and movable contacts which are engaged and disengaged with a quick, snappy movement even when the initial operating means for the switch is moved very slowly. I accomplish the objects of my invention by providing a swinging switch arm which carries the movable contact and which has a dead-center in combination with a movable member, which, when it passes over the dead-center in either direction, exerts a sudden thrust on the switch arm for opening or closing the switch according to the direction of movement of the movable member.

The full objects and advantages of my invention will appear in connection with the detailed description thereof, and the novel features of my inventive idea will be particularly pointed out in the claim.

In the accompanying drawings which illustrate one of the forms in which my invention may be embodied,—

Fig. 1 is a side elevational view of the switch in closed position. Fig. 2 is a similar view with small portions in section and showing the switch in open position. Fig. 3 is a front elevational view.

Referring to the construction shown in the drawings, the numeral 10 designates any suitable support upon which a fixed contact is mounted. When the support is constructed of metal or other conducting material, the fixed contact is insulatively mounted thereon. In the embodiment shown, this contact consists of a short, carbon cylinder 12 held in a split ring 14, the ends of which are held together by a screw 16 in order to clamp the ring on the contact. An arm 18 extends from the ring 14 opposite the split therein and this arm is perforated for the passage of a bolt 20 which passes through a strip 22 of insulating material interposed between the support 10 and the contact 12 and through insulating material 24 extending through a hole in the support 10 so that the contact 12 and the bolt 20 are insulatively mounted. The bolt 20 is utilized as a binding post for a wire 26 constituting one of the wires of an electric circuit which is to be controlled. An angular bracket 28 is insulated from the support 10 by insulating material 30 and is secured by bolts 32 and 34 which pass through portions of the insulating material

placed in holes in the support. The bolt 34 serves as a binding post for the other wire 36 of the electric circuit. A switch arm 38 is pivotally mounted in the bracket 28 by a pivot 40 passing through a circular marginal portion of the bracket and through a circular end portion of said arm. The other end of the arm 38 is made in the form of a split ring 42, the free end of which has a screw 44 passing therethrough in order that the ring may be clamped upon a carbon contact 46 which is held from sliding backwardly in the ring by a lug 48 formed thereon. The intermediate portion of the switch arm 38 has a widened portion 50 containing a V-shaped slot 52 which provides a shoulder 54 over which a roller 56 of fiber or other insulating material is adapted to run. This roller is grooved so as to be kept in engagement with the upper margin of the V-shaped slot and is mounted on a pin 58 secured to the end of a bar 58 adapted to be reciprocated or slid in any suitable manner. A coiled spring 60 attached to the pin 58 and to a projection 62 on the bracket 28 serves to hold the roller in stressed engagement with the upper margin of the slot 50. In the particular embodiment shown, the bar 58 may be reciprocated by a hand lever 64 pivotally attached thereto. This hand lever is intermediately pivoted to a fixed arm 66 which is shown as extending out from the bracket 28. It will be understood that the positioning of the handle 64 or other operating member will depend upon the manner in which the support 10 is mounted and that for some purposes, it will be desirable to have the handle mounted in front of instead of at the rear of the support. Furthermore, the member which carries the fiber roller may be reciprocated in other ways as, for instance, in the manner shown in the application for patent of Charles P. Strite for bread toasters filed July 10, 1926, Serial Number 121,693. A lug 68 extending transversely from the periphery of the circular end of the switch arm 38 serves as a stop to limit the extent of retraction of the contact 46 by engaging the bracket 28 when the switch is opened.

The operation and advantages of my invention will now be obvious. If the switch is in the closed position shown in Fig. 1 and it is desired to open the same, the bar 58 is moved rearwardly into the position

shown in Fig. 2 which causes the roller 54 to run over the shoulder 52. As soon as the roller has passed the dead-center it exerts a sudden thrust on the switch arm which results in the switch being opened with a quick, snappy action. When it is desired to close the switch, the reverse action occurs. When the switch is in closed position, it is obvious that current passes from a wire 26 to the engaged contacts 12 and 46, through the switch arm 38 to the bracket 28 and out through the wire 36. The direction of current may, of course, be in the reverse direction according to the manner in which the wires are connected with the source of electrical energy.

I claim:

An electric switch comprising a support, a fixed contact insulatively carried by said support, a bracket insulatively secured to said support and having a circular marginal portion, a switch arm having a circular end por-

tion, a pivot passing centrally through said circular portions, a stop lug extending transversely from the periphery of the circular portion of said arm and adapted to engage said bracket when said arm is in open position, said arm having an intermediate enlarged portion provided with a V-shaped slot therein forming a shoulder, a contact 30 carried by the other end of said arm and adapted to engage said fixed contact, a fiber roller positioned in said slot, a bar on one end of which said roller is mounted, a lever to which the other end of said bar is pivoted 35 and by which said roller may be moved across said shoulder, and a spring connecting said bracket and said bar which causes said roller to exert a sudden thrust on said switch arm when said roller passes 40 over said shoulder in either direction.

In testimony whereof I hereunto affix my signature.

THOMAS C. FORBES.
